Primary Examiner — Kendra Leslie Hamilton*Assistant Examiner* — Elizabeth S Struble(74) *Attorney, Agent, or Firm* — WENDEROTH, LIND & PONACK, L.L.P.(57) **CLAIM**

The ornamental design for a blood testing apparatus, as shown and described.

DESCRIPTION

FIG. 1 is a perspective view of a blood testing apparatus, showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The evenly spaced broken lines in the drawings depict portions of the blood testing apparatus that form no part of the claimed design.

1 Claim, 7 Drawing Sheets(56)
